UNITED STATES PATENT OFFICE.

GEORGE M. CLARK, OF HIGGANUM, CONNECTICUT.

POTATO-DIGGER.

SPECIFICATION forming part of Letters Patent No. 363,117, dated May 17, 1887.

Application filed April 14, 1886. Serial No. 193,781. (No model.)

To all whom it may concern:

Be it known that I, GEORGE M. CLARK, of Higganum, in the county of Middlesex and State of Connecticut, have invented a certain 5 new and useful Improvement Applicable to Potato-Diggers, of which the following is a description, reference being had to the accompanying drawings, where—

Figure 1 is a view of a potato-digger entire. 10 Fig. 2 is a detail view showing two of the rearwardly-extending fingers, hereinafter mentioned, also the blade and cleat to which they are attached, such blade and cleat being cut in vertical section. Fig. 3 is a detail view 15 showing a portion of the upper face of the said cleat, and also a portion of one of the rearwardly-extending fingers.

This potato-digging device may be attached to a cultivator-frame, which cultivator-frame 20 is shown in the drawings; but as there is no necessity for any detailed description of it, none will be given.

The letters *a a* denote parts of a cultivator-frame, and I will describe how the potato-digging parts are attached thereto.

The letters *b b* denote two small plows, which in the use of the tool are to go one upon each side of rows of potatoes which are to be dug, and they are so set as to turn the dirt away 30 from the potatoes.

The letter *c* denotes a horizontal blade extending between the plows *b b*, and its office is to run beneath the potatoes and lift them and the surrounding dirt from their resting-place.

35 The plows *b* and the blade *c* are all attached to the standards *d d* the plows to the outsides and the blades to the insides of the standards, which standards are so attached to the parts *a a* as to give the plows and blade a vertical ad-

justment with reference thereto; and to this 40 end the standards are pivotally attached to the parts *a a* by bolts *e*, which act as pivots. The front ends of the standards *d* are provided with a series of holes, *d'*, or an equivalent slot, through which, and also through the parts *a*, 45 runs a bolt, *e'*, by means of which the plows and the blade can be secured at any desired point in their said vertical adjustment.

From the rear side of the blade *c* extends two series of fingers. The series *f* lie in one plane 50 and the series *f'* lie in another plane. The fingers of series *f* alternate with the fingers *f'* in the points of their attachment to the blade. By locating these fingers in two series in this manner the delivery of dirt and stones is 55 greatly accelerated. All of these fingers are attached to the blade in the same manner, and that a peculiar manner. The front end of each finger has an enlargement, *f''*. These fingers are all clamped to the blade *c* by the cleat *g*, 60 drawn toward the blade by appropriate bolts or screws. This cleat is provided on the upper side with lugs *h*, which extend from finger to finger in rear of the enlargements *f''*, thereby preventing the fingers from being drawn 65 rearwardly out of place.

I claim as my improvement—

In combination, in a potato-digger, the frame-bars *a*, standards *d*, pivoted to frame-bars at *e*, bolt-holes *d'*, bolt *e'*, plows *b*, attached to outsides of standards, and blade *c*, attached to insides of standards and provided with rear fingers, *f*, all substantially as described, and for the purpose set forth.

GEORGE M. CLARK.
